UNITED STATES PATENT OFFICE.

BRIDGET RYAN, OF LONG ISLAND CITY, NEW YORK.

DESIGN FOR A DRESS-SHIELD.

SPECIFICATION forming part of Design No. 35,398, dated December 3, 1901.

Application filed April 29, 1901. Serial No. 58,079. Term of patent 7 years.

To all whom it may concern:

Be it known that I, BRIDGET RYAN, a citizen of the United States, residing at Long Island City, in the county of Queens and State of New York, have invented and produced a new and original Design for a Dress-Shield, of which the following is a specification, reference being had to the accompanying drawings, forming part thereof.

10 The leading feature of my design is a dress-shield of substantially the configuration and representation shown in the drawings.

In the accompanying drawings I have shown a dress-shield embodying my design.

15 In the drawings, Figure I is a side or face view of the dress-shield, and Fig. II is a view of the opposite face.

In the drawings, A indicates the body of the dress-shield, having a scalloped full lower portion, shown in the drawings as below the line $x x$ in Fig. I. This lower A portion is 20 formed with a large scallop at the lowermost portion thereof, flanked on each side by scal-

lops f.. Projecting upward from the lower portion, on each side thereof, are curved tapered tabs b. The curved inner edges c of the tabs b join the curve d of the full lower portion of the shield, and the outer curved edges e of the said tabs formed with the outer curved edges of the scallops f of the shield reentrant 25 angles g.

The width of the tapered curved tabs b as represented, for instance, along the line y y is considerably less than the width of the full lower or body portion as represented by the 30 line z z.

What I claim is—

15 The design for a dress-shield substantially as herein shown and described.

In testimony whereof I have signed my 40 name to this specification in the presence of two subscribing witnesses.

BRIDGET RYAN.
